UNITED STATES PATENT OFFICE

ERRIS FRANKS, OF LONDON, ENGLAND

DESIGN FOR A TRAVELING RUG

Application filed June 21, 1930, Serial No. 36,125, and in Great Britain March 6, 1930. Term of patent 7 years.

To all whom it may concern:

Be it known that I, ERRIS FRANKS, a Russian subject, residing at 107 Queens Road, Bayswater, London, W., England, have invented a new, original, and ornamental Design for a Traveling Rug, of which the following is a specification, reference being had to the accompanying drawing, forming part thereof.

The figure is a plan view of a traveling rug showing my new design.

The opposite side of the rug is plain.

I claim:

The ornamental design for a traveling rug, as shown and described.

ERRIS FRANKS.
